RADIO RECEIVING CIRCUITS

Kenneth W. Jarvis, Chicago, Ill., assignor to
 Radio Corporation of America, New York,
 N. Y., a corporation of Delaware

Application September 28, 1934, Serial No. 745,880

15 Claims. (Cl. 178—44)

My invention relates in general to radio circuits and more particularly to radio receiving circuits.

An object of my invention is to improve the 5 quality of radio reception.

A further object of my invention is to provide for obtaining a substantially uniform response with respect to frequency over a relatively wide band of frequencies.

10 Another object of my invention is to provide for varying the coupling between a plurality of resonant circuits and for maintaining the over all mean resonant frequency at substantially the same value, as the coupling is varied.

15 It is also an object of my invention to provide for varying the coupling between a plurality of resonant circuits and for modifying the resonant circuits to maintain the over all mean resonant frequency at substantially the same value, 20 as the coupling is varied.

Another object of my invention is the provision of a plurality of resonant circuits coupled together and arranged to have a certain over all mean resonant frequency and a certain over 25 all response with respect to frequency, taken in combination with controllable means for modifying the resonant circuits to give a different over all response with respect to frequency, while maintaining substantially the same over all mean 30 resonant frequency.

A still further object of my invention is the provision of a plurality of resonant circuits coupled together and arranged to receive a band of incoming frequencies having a mid-frequency 35 value, said circuits being also arranged to have a certain over all mean resonant frequency of substantially the same value as the mid-frequency value and a certain over all response with respect to incoming frequencies, taken in combination with controllable means for modifying 40 the resonant circuits to give a different over all response with respect to incoming frequencies while maintaining the over all mean resonant frequency at substantially the same value as the mid-frequency value.

45 A further object of my invention is the provision of a plurality of resonant circuits coupled together and arranged to receive a band of incoming frequencies having a mid-frequency value, 50 said circuits being also arranged to have a certain over all mean resonant frequency of substantially the same value as the mid-frequency value and a certain over all response with respect to incoming frequencies taken in combination with controllable means by varying the

coupling and for modifying the resonant circuits to give a different over all response with respect to incoming frequencies while maintaining the over all mean resonant frequency at substantially the same value as the mid-frequency 5 value.

Another object of my invention is the provision of variable coupling for resonant circuits, which coupling modifies the resonant circuits, as the coupling value is varied.

10 A still further object of my invention is to improve the response with respect to frequency of an intermediate frequency amplifier of a radio receiving circuit.

15 Another object of my invention is to provide for receiving the modulation side band frequencies at substantially equal amplitude.

Other objects, and a fuller understanding of my invention may be had by referring to the following description, taken in conjunction with 20 the accompanying drawings in which;

Figure 1 is a diagrammatic illustration of the circuit connections, embodying the features of my invention.

25 Figure 2 is an illustration of a "critical" response curve with respect to frequency, and illustrates the general form of the response with respect to frequency, as given by my invention, when operated in its "sharp" tuning position.

Figure 3 is a "broad" response curve with 30 respect to frequency, and illustrates the ideal or theoretical type.

Figure 4 is a "broad" response curve with respect to frequency, and illustrates in general the shape of a response curve with respect to 35 frequency, as given by my invention and being an approximation to the ideal response curve as shown in Figure 3.

Figure 5 is a "broad" response curve with respect to frequency, and illustrates in general the 40 shape of a response curve with respect to frequency as given by the preferred form of my invention and being an approximation to the ideal response curve as shown in Figure 3.

Figure 6 illustrates the variations in the value 45 of the two resonant frequencies, and also the shifting of the mean resonant frequency from the mid-frequency value as the coefficient of coupling is varied between the resonant circuits.

Figure 7 illustrates an intermediate frequency 50 amplifier of a radio receiving circuit, embodying features of my invention.

Figure 8 illustrates a fragmentary and a modified view of the switches that are adapted to control the circuits of Figure 7.

Figure 9 is a modified form of my invention, wherein a tube is employed as a coupling between two resonant circuits.

Figure 10 is a further modified view of my invention, wherein a tube is utilized as a coupling between two resonant circuits, and

Figure 11 is an illustration of a coupling device between two resonant circuits, which coupling device modifies the condition of the two resonant circuits as the coupling is varied.

In the present state of the art, a radio transmitter produces, when no modulation is taking place, an undamped current of a constant amplitude and of a single frequency, except for any harmonics that might be present. This undamped current is normally referred to as the carrier current. However, when modulation takes place there are two groups of modulation frequencies extending one on either side of the carrier frequency. These two groups of frequencies, which have a mean frequency value equal to the frequency of the carrier current, are generally referred to as side band frequencies. The group with a frequency higher than the carrier frequency is called the upper side band and the group with a frequency lower than the carrier frequency is called the lower side band. It is to be noted that the side bands extending on either side of the carrier frequency have a number of cycles equal to that of the microphone modulating circuit.

Inasmuch as the current in the receiving system is to be a reproduction of that in the transmitting antenna, it follows that the receiving system circuits must not be sharply tuned to any one frequency, to the partial or entire exclusion of other frequencies, but must be so designed as to be able to pick up all of the various side band frequencies with a uniform response, and to exclude frequencies differing from the carrier frequency by more than the frequency of modulation. This means that if the difference between the maximum and minimum frequencies, expressed as a percentage of the carrier wave frequency, is very large the tuning of the receiving circuit must be broad in order for it to have a substantially uniform response throughout a wide range of side band frequencies.

In Figure 2 of the drawings, I illustrate generally, by the full line 31, the shape of a response curve when the receiving circuits are sharply tuned. The shape of the frequency response curve 31, it will be seen, is such that a comparatively short range of the lower modulation side band frequencies on either side of the carrier frequency will pass through the tuned circuit with uniform response. The higher modulation side band frequencies will be attenuated by reason of the sloping sides of the response curve, so that these frequencies are not passed through with uniform response. It will be clear therefore that good audio quality reproduction will not result with a tunable circuit or circuits having a peaked frequency response curve such as 31.

In Figure 3 I illustrate an ideal response curve. It is manifest, in this connection, that the response is uniformly received throughout the entire range of the lower and the upper side band frequencies. The width of the ideal response curve in Figure 3 may be of any desired value. In the present state of the art, a satisfactory value may be about 15 kilocycles. This makes the width of each of the side band frequencies $7\frac{1}{2}$ kilocycles, and thus gives a very excellent quality of reproduction. Therefore, in Figures 2 and

3 of the drawings, the outer ranges of frequencies which fall outside of the desirable frequency range are indicated as being the undesirable frequency ranges.

When listening to close or strong transmitting stations it is preferable to have the radio receiving circuits broadly tuned, so as to give good reception, but when listening to distant or weak stations, it is often desirable to have the receiving circuits sharply tuned, in order to be able to eliminate interference and to hear the station, even though the reception is not so good as it is with broad tuning. Therefore, in the practice of my invention, I provide a receiving circuit having two or more degrees of selectivity, so that the user may selectively operate the receiving circuit to accommodate best his requirements. Such a receiving circuit comprising the usual inductance and capacity is diagrammatically illustrated in Figure 1 of the drawings. In this arrangement, the resonant circuit No. 1 is impressed with and adapted to receive the incoming upper and lower modulation side band frequencies of a transmitted signal. As the incoming current passes through the resonant circuits No. 1, No. 2, No. 3 and No. 4, there is produced a certain over all response with respect to frequency, which is transmitted upon leaving the resonant circuit No. 4, to the audio system and then translated into sound. The couplings No. 1, No. 2 and No. 3 may comprise mutual capacity or inductance, or external capacity or inductance, or their combination, or any other circuit element or elements, or relay devices, such as tubes to give the desired effect. Each of the modifiers may comprise capacity or inductance, or any other circuit element or elements connected in any desirable circuit relation with the elements of the resonant circuits.

As illustrated, the coupling No. 1 and the modifiers No. 1 and No. 2 may be simultaneously operated as indicated by the dash line 20, and similarly the coupling No. 3 and the modifiers No. 3 and No. 4 may be simultaneously operated as indicated by the dash line 21. As further indicated by the dash lines 22, 23 and 24 and by the interconnecting arrows 25 and 26, the coupling No. 1 and the modifiers No. 1 and No. 2 may be operated either independently of, or simultaneously with, the coupling No. 3 and the modifiers No. 3 and No. 4.

For the purpose of discussion, let it be assumed first that the coefficient of coupling of the coupling No. 1 and the coupling No. 3, is relatively low, that is, giving what is commonly called "loose" coupling. Under this condition, as is well known in the art, the over all response for the resonant circuits No. 1, No. 2, No. 3 and No. 4 is relatively sharp, having a shape similar to the full line response curve 31 shown in Figure 2. Under the condition of relatively "loose" coupling, the over all mean resonant frequency, which is the correct tuning position, is substantially the same as the mid-frequency value of the modulation side band frequencies of the incoming signal impressed upon the amplifier. This is shown by the curves of Figure 6. In other words, the correct tuning position is attained by making the over all mean resonant frequency value coincide substantially with the mid-frequency value.

Let it now be assumed that the coefficient of coupling between the resonant circuits No. 1 and No. 2, and the coupling between the resonant circuits No. 3 and No. 4 is materially increased,

thus giving what is usually termed "close" coupling. Under this assumed condition, as is well known in the art, there are produced two resonant peaks, such as is shown by the dash line 33 in Figure 2, instead of the single resonant peak, as shown by the full line 31 in Figure 2. The amplitude of these two resonant peaks and their respective frequencies, and the dip between them, all depends on the various circuit constants. In practice, the various circuit constants are so proportioned that the width of the "broad" response is sufficiently wide to include all of the incoming modulation side band frequencies. Accordingly this method provides a means of obtaining a more uniform response over the desired frequency band than the sharply tuned circuit. However, the over coupling method has at least one major disadvantage, in that, as the coefficient of coupling is increased, the over all mean resonant frequency of the resonant circuits, which is the correct tuning position, shifts from the mid-frequency value of the modulation side band frequencies of the incoming signal. This is shown by the curves of Figure 6. The curves indicated by the reference characters f_1 and f_2 show where the resonant frequencies occur; that is, where the peaks of the coupled resonant circuits appear. As illustrated, when the value of the coefficient of coupling is increased to unity the curve f_1 approaches infinity, while the curve f_2 decreased to a value somewhat less than its original frequency.

The net result of this over coupling is to make one resonant peak shift very rapidly from the mid-frequency value, while the other resonant peak shifts very slowly in the opposite direction from the mid-frequency value. In other words, the over all mean resonant frequency, which for a particular coefficient of coupling is the arithmetical mean or average frequency between the resonant peak frequencies and is indicated by the dash line 32 in Figure 6, deviates from the mid-frequency value. As is manifest, when the unequal shift in the resonant peaks occurs by reason of the over coupling, the individual modulation side band frequencies are not received with equal amplitude, nor is the phase shift of the equal plus and minus modulation side bands frequencies the same. Both of these asymmetrical effects give distortion in the received signal. However, in my invention by the utilization of the modifiers No. 1, No. 2, No. 3, and No. 4, as indicated generally in Figure 1, I provide for maintaining the over all mean resonant frequency at substantially the same value as the mid-frequency value, regardless of the value of the coefficient of coupling. This means that there is no distortion in the received signal. In actual practice, I find that the modifiers may conveniently comprise the adding, or the subtracting, external inductance or capacitance, or any other circuit constants, with the elements of the resonant circuits. But it is to be understood that the modifiers of my invention are not limited to the addition or subtraction of external inductance or capacitance to the elements of the resonant circuits. The modifiers may comprise other equivalent means.

In the operation of my invention, let it be assumed that it is desirable to employ a "broad" response, such as indicated by the substantially rectangular curve 34 of Figure 4. This may be accomplished by simultaneously actuating the coupling No. 1 and the modifiers No. 1 and No. 2 to such position that the coefficient of coupling is relatively large, and by allowing the coupling No.

3 and the modifiers No. 3 and No. 4 to remain in a "loosely" coupled position. Under this condition, it is manifest that the combined action of the closely coupled resonant circuits No. 1 and No. 2, together with the modified or reshifting action of the modifiers No. 1 and No. 2 produce a "broad" response curve having two peaks and having a mean resonant frequency value substantially equal to the mid-frequency value, such as that shown generally by the dash line curve 27, of Figure 4. It is also observed that, since there is a "loose" coupling between the two resonant circuits No. 3 and No. 4, a relatively sharp single resonant peak is produced, such as the one indicated by the dash line curve 28 of Figure 4. The over all response of the resonant circuits No. 1, No. 2, No. 3 and No. 4 is given by multiplying the amplitudes of the two curves 27 and 28 of Figure 4. This gives a relatively "broad" response curve 34, similar in shape to the ideal curve as shown in Figure 3. In Figure 4, it is pointed out that the "broad" response curve 27, as produced by the two resonant circuits No. 1 and No. 2, has a mean resonant frequency value that coincides substantially with the mid-frequency value, as indicated by the centrally positioned vertical line. In this connection, it is to be noted that, if the modifiers No. 1 and No. 2 were not simultaneously actuated with the actuation of the coupling No. 1, the broad response curve 27 would be shifted to such a position that its mean resonant frequency value would not coincide with the mid-frequency value. This shifted condition, as pointed out before, if allowed to exist, would cause distortion in the received signal.

A complete operating circuit embodying the preferred features of my invention, which produce a "broad" band, flat top response, is shown in Figure 7. This embodiment of my invention is based upon the form, illustrated diagrammatically in Figure 1 of the drawings, and is incorporated in the intermediate frequency amplifier of a radio receiving circuit.

The receiving antenna and the ground connection therefore, are indicated by the reference characters 40 and 41, respectively. The reference character 42 designates the radio frequency amplifier and the reference character 43 indicates the heterodyne device. As is well known in the art, the combined action of the radio frequency amplifier and the heterodyne device produces an intermediate frequency, having a mid-frequency value with the modulation side band frequencies extending on either side. The first detector tube is indicated by the reference character 44. As illustrated, this detector tube comprises a control grid 45, a cathode 46, a screen grid 47, a suppressor grid 48 and a plate 49. The cathode 46 of the tube has the customary by-pass condenser 54 and a self biasing resistor 55, connected to a ground 56. The batteries 57 and 58, or other suitable source of supply, furnish voltage to the plate 49 and the screen grid 47 of the detector tube 44. The plate 49 is connected to the high sides of a resistor 51, a tuning inductance 52 and a normal tuning, adjustable condenser 53. As illustrated, the lower ends of the resistor 51 and the tuning inductance 52 are connected through a by-pass condenser 59 to a ground 60. The condenser 63 is a modifier condenser, and corresponds to the modifier No. 1 of Figure 1. The condenser 64 is the normal capacity coupling, and when used gives a relatively "sharp" response curve similar to the dash curve 28 of Figure 4 of the drawings. The condenser 65 is the mutual

capacity to over couple the resonant circuits and when used gives a relatively "broad" response curve, similar to the dash curve 29 of Figure 5; assuming, of course, that the circuit constants are such that they produce this shape of response. The shifting from the coupling condenser 64 to the coupling condenser 65, and vice versa, corresponds to the action afforded by the variable coupling No. 1 of Figure 1. The adjustable condenser 67 is the grid or input side tuning condenser, and the condenser 68 is a modifier condenser and corresponds to the modifier No. 2 of Figure 1. The reference character 69 indicates the grid tuning inductance and the low potential end thereof is by-passed through the large condenser 72 to the ground 73. As illustrated, the inductance 52 is shielded by a shield 61 that is connected to a ground 62, and the inductance 69 is likewise shielded by a shield 70 that is connected to a ground 71. This serves to isolate the two inductances 52 and 69. The point 135 of the low potential end of the inductance 69 is connected to the automatic volume control system 133 by means of a conductor 134. This automatically controls the grid bias of the tube 86, which may be similar to the first detector tube 44. As shown, the tube 86 comprises a cathode 87, a control grid 88, a screen grid 89, a suppressor grid 90 and a plate 91. The tube 86 serves to amplify the voltage across the inductance 69 and impress it upon the next selective unit. The cathode 87 of the tube 86 is connected directly to a ground 92, as this tube receives its bias voltage through the automatic volume control system 133. The batteries 93 and 94 furnish voltage to the plate 91 and the screen grid 89, and they may be in common with the batteries 57 and 58. The plate 91 of the tube 86 is connected to the high sides of the tuning inductance 95 and the adjustable condenser 100. As illustrated the low potential end of the tuning inductance 95 is connected through a by-pass condenser 98 to a ground 99, and is shielded by a shield 96 which is connected to a ground 97. The condenser 101 is the modifier condenser in the plate tube circuit and corresponds to the modifier No. 3 of Figure 1. The reference character 102 indicates a resistor. The reference character 105 designates a coupling inductance which serves to over couple the two resonant circuits. In this case, I utilize an inductance in order to reverse the resonant peaks from that of the first selective unit; see the reverse resonant peaks of curves 29 and 30 of Figure 5. The condenser 106 is the normal capacity coupling and when used gives the sharp selective response, as illustrated generally by the dash curve 28 of Figure 4. This condenser 106 is connected to a ground 107. The shifting from the coupling condenser 106 to the coupling inductance 105, and vice versa, corresponds to the action afforded by the variable coupling No. 3 of Figure 1. The adjustable condenser 103 is the grid tuning condenser, and the condenser 104 is the modifier condenser and corresponds to modifier No. 4 of Figure 1. The reference character 113 designates the grid tuning inductance and is connected to a ground 116, and is shielded by shield 114 which is connected to a ground 115. The voltage across the grid tuning inductance 113 is fed to the amplifier tube 117, which comprises a cathode 118, a control grid 119, a screen grid 120, a suppressor grid 121 and a plate 122.

The cathode 118 has the customary by-pass condenser 124 and a self biasing resistor 123 connected to a ground 125. The batteries 126 and 127

furnish voltage to the plate 122 and the screen grid 120, and may be in common with the other batteries. The plate 122 is connected to the tuned circuit comprising an adjustable condenser 129, an inductance 130 and a shunting resistor 128. The inductance 130 is coupled to the inductance 131, which, in turn, feeds voltage into the second detector and audio system 132 and the automatic volume control system 133.

The switches 77 and 111 serve to give two degrees of selectivity and correspond to the arrows 25 and 26 of Figure 1. Their action will now be described. When the switch 77 is turned so that the center contact 79 is connected to the two conductors 74 and 76, the circuit is in the "broad" tuning position. In this position of the switch, the normal coupling condenser 64 and the modifier condensers 63 and 68 are shorted or excluded from the resonant circuits. The resonant circuit, which may be designated as the one corresponding to the resonant circuit No. 1 of Figure 1, may be traced as follows: Beginning with the ground 60, the circuit extends through the condenser 59, and in parallel through the inductance 52 and the resistor 51, the adjustable tuning condenser 53, the conductor 74, the switch 77 to the center contact 79, the conductor 75, the condenser 65, to the ground 66. The resonant circuit which may be designated as the one that corresponds to the resonant circuit No. 2 of Figure 1, may be traced as follows: Beginning with the ground 66, the circuit extends through the coupling condenser 65, the conductor 75, the switch 77, the conductor 76, the adjustable condenser 67, the inductance 69, the by-pass condenser 72 to the ground 73. The condenser 65, which is relatively small in capacity, serves to over couple the resonant circuits and thus give a response similar to that indicated by the dash curve 29 of Figure 5. The relative amplitude of the two peaks is affected by the various impedance conditions in the system. That is, the inductance—capacity ratio and the effective resistance of each resonant circuit each have a modifying effect on the relative peak amplitude and shape of the response curves. The resistor 51 is used to lower the input impedance even more than is accomplished by the L—C ratios in the resonant circuits, and makes one of the resonant peaks of the coupled resonant circuits lower than the other, see the dash curve 29 of Figure 5.

When the switch 77 is turned so that its center contact 79 is connected to the ground 78 the resonant circuits are in their "sharp" tuning position. In this position the small condenser 65 is shorted, and the relatively large condenser 64 constitutes the coupling between the two resonant circuits. As the condenser 64 is relatively large, only one resonant peak results, being similar to the response shown by the dash curve 28 in Figure 4. It is also noted that, when the center contact 79 is grounded, the modifier condensers 63 and 68 are added to the resonant circuits. The action of these added modifier condensers 63 and 68 is such that they modify the resonance frequency of the circuits, and thus maintain the mean resonant frequency at substantially the same value as the mid-frequency value of the modulated side band frequencies. This means that the correct tuning position is always maintained. This would not be the case, if the mean resonant frequency were shifted from the mid-frequency of the modulated side band frequencies. In practice the condensers 63, 64, 65, and 68, since they are not so critical, are made 75

fixed units, the values thereof being determined by the design of the receiving circuits. The adjustable condensers 53 and 67 are used to tune the resonant circuits when in the sharp resonant position. This is done during the process of manufacturing, and when once tuned they remain fixed. The simplicity of tuning and the non-criticalness of the values of the various circuit elements of my resonant circuits, insures a good quality of reproduction throughout a relatively wide range of manufacturing tolerances on the condensers 63, 64, 65, and 68.

The action of the switch 111 is essentially the same as that of switch 77, but of a reverse order. As illustrated by the dash line 81, the switches 77 and 111 are ganged together, but may be made to work independently of each other, or in sequence in case more than two degrees of selectivity are desired. When the switch 111 is turned such that the center contact 80 is connected to the conductors 108 and 110 the resonant circuits are placed in their "sharp" tuning position and give a response similar to the dash curve 28 of Figure 4. In this position, the modifier condensers 101 and 104 and the resistor 102, and the over coupling impedance 105 are shorted, and only the normal tuning inductance 95 and the normal tuning capacity 100, and the normal tuning inductance 113 and the normal tuning condenser 103, and the normal coupling condenser 106 are effective. The resonant circuits are tuned in this selective or "sharp" resonant condition during the manufacturing process by adjusting the tuning condensers 100 and 103, and when once adjusted they remain fixed. It is to be noted that in this position the mean resonant frequency of these circuits substantially coincides with the mid-frequency value of the modulated side band frequencies.

When the switch 111 is turned so that the center contact 80 is connected to the ground 112, the circuits are "broadly" tuned, and the normal coupling condenser 106 is shorted, and the over coupling inductance 105 is connected in circuit relation with the two resonant circuits. In over coupling, the tendency normally is to push the mean resonant frequency of the two resonant circuits to a higher value, but in this case, by reason of the large value of the added inductance 105, the mean resonant frequency is pushed below the mean resonant frequency of the normally critically tuned resonant circuit. Therefore, it is necessary under this condition to add the modifier condensers 101 and 104 to the resonant circuits in order to raise the mean resonant frequency value to substantially the same as the mid-frequency value of the modulated side band frequencies. It is to be noted that, by utilizing an inductance, instead of a capacitance in over coupling the resonant circuits, the resonant frequency peaks are just reversed. Compare curve 29 and 30 of Figure 5. The resistor 102 is used to lower the input impedance even more than is accomplished by the use of the L-C ratios in the resonant peaks of the dash curve 30 of Figure 5 to be lower than the other. The resistor 102 serves substantially the same function with reference to its own resonant circuits as the resistor 51 served with its own resonant circuits, and therefore could be placed in parallel circuit connection with the tuning inductance 95. However, in the series position as shown, the resistor 102 is effective only in the "broad" tuning position, and thus ineffective in the "sharp" tuning position, with the result that in the "sharp" tun-

ing position the resistor 102 has no resistive action on the resonant circuits.

It is noted from the function of the switches 77 and 111 that, when both of them are turned in their "broad" position, a response curve similar to that shown in Figure 5 is given by the entire circuit, and that, when the switches are turned to their sharply tuned position, a response is given similar to the full line 31 curve in Figure 2. Therefore, my invention is such that it gives two degrees of selectivity, and that when positioned in the "broad" tuning position the response is substantially uniform through the modulated side band frequencies.

In Figure 8, I illustrate a fragmentary view of a modified set of switches which give three selective positions. In the modified arrangement, the two switches 136 and 142 are ganged together as indicated by the dash line 143. In the switch 136, the contact segments 139 and 140 are relatively long and the contact 141 is relatively short, and in the switch 142 the contact 145 is relatively short and the contacts 146 and 147 are relatively long. Therefore, by the arrangement of these contact segments, the switches are so designed that, in the position shown, the two sets of resonant circuits are broadly tuned. In an intermediate position, the set of resonant circuits associated with the switch 136 is broadly tuned as the contact segments 139 and 140 are still bridged, but the set of resonant circuits associated with the switch 142 is sharply tuned as the center contact 144 is connected to the two conductors 108 and 110. In the third position, the sets of resonant circuits are both sharply tuned, as the center contact of the switch 136 is connected to the ground 137 and as the center contact of the switch 142 is still connected to the conductors 108 and 110. In this manner there are three selective tuning positions. However, if more than three selective tuning positions are desired, this may be accomplished by utilizing a stepped coupling unit and a stepped system of modifiers. Also, while the physical size may be somewhat large, a continuous change from one degree of tuning may be made to another degree of tuning by providing a continuous system of variable couplings and variable modifiers.

In Figure 1 it is noted that the resonant circuit No. 2 and the resonant circuit No. 3 are coupled by a coupling No. 2. As before mentioned, this coupling No. 2 may comprise an amplifying tube. The embodiment of a circuit utilizing the relation that exists between the resonant circuit No. 2 and the resonant circuit No. 3, together with the coupling No. 2 is shown in Figure 9. In this figure, the antenna and the ground therefore are designated by the reference characters 157 and 158, respectively. The radio frequency amplifier 159 and the heterodyne device 160 jointly act to impress an intermediate frequency having a mid-frequency value, with modulated side bands on either side, upon the first detector tube 161. The cathode 197 has the customary bypass condenser 198 and a self biasing resistor 163 connected to a ground 162. The batteries 195 and 196 supply voltage to the plate 155 and the screen grid 154. The condenser 164 is a by-pass condenser. The tube 170 corresponds to the coupling No. 2 of Figure 1. The cathode 199 has the usual by-pass condenser 174 and the self biasing resistor 173 connected to the ground 175. The illustrated batteries 152 and 153 supply voltage to the plate 172 and the screen grid 151. The condensers 176 and 183 are by-pass condensers.

The inductance 165 and the adjustable condenser 167 comprise the active elements of a resonant circuit that corresponds with the resonant circuit No. 2 of Figure 1. The inductance 178 and the condenser 180 comprise the active elements of a resonant circuit that corresponds to the resonant circuit No. 3 of Figure 1. As illustrated, the low potential end of the condenser 180 is connected through a by-pass condenser 181 to a ground 182. 10 The condenser 168 is a modifier condenser, and corresponds to modifier No. 2 of Figure 1. The condenser 166 prevents the batteries 195 and 196 from influencing the grid 171 of the tube 170, and the condenser 179 is a similar blocking condenser. The reference character 169 designates a high resistance connected between the ground 175 and the grid 171 of the tube 170.

The resonant circuit of Figure 9 is designed to have two degrees of selectivity, and is controlled 20 by the switch 184 having a movable bridge member 189 adapted to contact the three contacts 186, 187 and 188. In the open position of the switch as shown, the circuits are sharply tuned, and give a response similar to the full line curve 25 31 of Figure 2. In the sharply tuned position, the modifier condenser 168 and the modifier inductance 177 are included in the resonant circuit. These resonant circuits are tuned to give a "sharp" 30 response when the switch 184 is open, during the course of the manufacturing process by the adjustable condensers 167 and 180, and when they are once set they remain fixed. In the "sharp" 35 position, the mean resonant frequency value of the two resonant circuits coincides substantially with the mid-frequency value of the modulated side band frequencies.

When the switch 184 is turned so that the bridge member 189 contacts the three contacts 186, 187 and 188, the over all circuit is broadly tuned. 40 This is effected by shunting the modifier condenser 168 and the modifier inductance 177. It is noted that the shunting of the modifier condenser 168 and the modifier inductance 177, in effect, performs two functions, in that the shunting not only produces a "broad" response which 45 may be similar to the dash curve 27 of Figure 4, but also maintains the mean resonant frequency value of the resonant circuits at substantially the same value as the mid-frequency of the modulated side band frequencies, for the reason that the exclusion of the modifier condenser 168 causes one of the resonant peaks to shift in one direction 50 from the mid-frequency value the same amount as the exclusion of the modifier inductance 177 causes the other resonant peak to shift in the opposite direction. The two equally and opposite shifted resonant peaks produce an over all response similar to the dash curve 27 of Figure 4. This means that there is no asymmetrical distortion 55 in the received signal. Also, it is noted that upon the closing of the switch 184 a resistor 194 is connected in parallel with the self biasing resistor 173. This causes the amplitude of the "broad" response curve to be elevated, for the reason that the tube 170 passes more current resulting from 60 the changed self biasing effect of the cathode 199.

In Figure 10, I illustrate a modified form of Figure 9. In this form the tube 212 feeds the tube 213 through means of loosely coupled resonant 65 circuits 205 and 206, which comprise, respectively, the inductance 208 and adjustable condenser 207, and the inductance 210 and an adjustable condenser 209, and the tube 213 feeds the second detector and audio system through means of the 70 loosely coupled resonant circuits 214 and 215,

which, respectively, comprise the inductance 217 and the adjustable condenser 216, and the inductance 219 and the adjustable condenser 220. The cathode of the tube 213 is connected directly to the ground 223, as the grid of the tube 213 is automatically biased by the automatic volume control system through a conductor 230. The tube 213 is the coupling tube, and corresponds to the coupling No. 2 of Figure 1. The condenser 211 is a modifier, and corresponds to the modifier No. 2 of 10 Figure 1. The inductance 218 is a modifier, and corresponds to the modifier No. 3 of Figure 1. The condensers 224, 222, and 221 are blocking condensers. This circuit has two degrees of selectivity similar to that of the circuit in Figure 9. 15 Both the "sharp" response and the "broad" response are controlled by the switch 225 which comprises two contacts 226 and 227 bridged by the contact member 228 which is connected to a ground 229. In the position shown in Figure 10, 20 the circuits are sharply tuned to give a response curve similar to that shown by the full line 31 in Figure 2. When in this position it is noted that the modifier condenser 211 and the modifier inductance 218 are included in the resonant circuit, 25 and it is in this position that the adjustable condensers 207, 209, 216 and 220 are tuned during the process of their manufacture. They are so adjusted, when in the sharply tuned position, that the mean resonant frequency value coincides substantially with the mid-frequency value of the modulated side band frequencies. 30

When the switch 225 is turned so that the bridge member 228 bridges the two contacts 226 and 227, the circuits are broadly tuned, and produce a response curve similar to the dash curve 27 of Figure 4. In this position the modifier condenser 211 and the modifier inductance 218 are shorted. The exclusion of the modifier condenser 211 and the modifier inductance 218 performs two functions, in a manner similar to the two functions 40 performed by the circuit in Figure 9, in that the shunting of these elements not only produces a "broad" response, but also maintains the mean resonant frequency value of the resonant circuits 45 at substantially the same value as the mid-frequency of the modulated side band frequencies. It should be noted that the same effect can be obtained by turning in the "sharp" position with the modifiers out, and then getting the "broad" 50 position by inserting the modifiers. This is just the reverse of the above description.

In Figure 11, I illustrate a coupling device which performs two functions, in that it not only varies the coupling between the resonant 55 circuits but also simultaneously produces the modifying action upon the resonant circuits to maintain the mean resonant frequency value of the two resonant circuits substantially the same as the mid-frequency value of the modulated side band frequencies. This coupling may comprise two movable coils 239 and 240 placed between two current conducting plates 243 and 244. The adjustable condensers 241 and 242 are adjusted during the course of their manufacturing to give a "sharp" tuning, when the coils 239 and 240 are separated to give a "loose" coupling condition. As the coils 239 and 240 are moved closer together the coupling between them is increased to produce a "broad" response; 60 but at the same time the coils themselves move farther away from the two spaced plates 243 and 244, which causes their self inductance to be greater, thereby producing a modifying action 65 upon the resonant circuits which maintains the 70 75

mean resonant frequency value substantially the same as the mid-frequency value of the modulated side-band frequencies. The operation of the two tubes 235 and 236, together with their associated circuits is substantially the same as that previously described with reference to the other circuits. It is noted that this coupling device produces as the coils 239 and 240 are moved toward each other, a gradual change from a sharply tuned circuit to a broadly tuned circuit, while at the same time maintains the mean resonant frequency value at substantially the same value as the mid-frequency of the modulated side band frequencies.

15 Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. In combination, a pair of resonant circuits, means including a common coupling reactance for over coupling the pair of resonant circuits so that they have a certain over all response with respect to frequency in which the higher resonance peak predominates, and have a certain over all mean resonant frequency, a second pair of resonant circuits, means including a common coupling reactance for over coupling the second pair of resonant circuits so that they have a certain over all mean resonant frequency and have a different over all response with respect to frequency from the response of the first pair of resonant circuits in which the lower resonance peak predominates, a vacuum tube amplifier and circuit connections for connecting the two pairs of resonant circuits thereto, and circuit modifying means associated with the several resonant circuits for maintaining the over all mean resonant frequency of the first pair of resonant circuits substantially the same 45 as the over all mean resonant frequency of the second pair of resonant circuits.

2. In combination, a first pair of coupled tuned circuits, common coupling reactance between said circuits, a second pair of coupled tuned circuits and common coupling reactance therebetween, an auxiliary reactance included in each of the tuned circuits, a coupling device interconnected between said two pairs of circuits, and switch means associated with the 55 auxiliary and coupling reactances, said switch means in one position operating to short-circuit the auxiliary reactance in each tuned circuit of the first pair only and to vary the common coupling reactances of both pairs of circuits, and in a second position operating to short-circuit the auxiliary reactance in each tuned circuit of the second pair only and to vary the common coupling reactances of both pairs of circuits, said mentioned means being operated in unison 60 to compensate for a shift in the mean resonant frequency caused by overcoupling in each pair of circuits.

3. The combination defined in the preceding claim wherein in a third position of the switch 70 means the auxiliary reactances of all the tuned circuits are short-circuited and the common coupling reactances of both pairs of coupled circuits are varied.

4. In combination, a pair of coupled tuned 75 circuits, each having an inductance, said in-

ductances arranged to be moved in an axial direction closer together or farther apart whereby the degree of coupling between the tuned circuits is varied, and a pair of spaced but immovable current conducting plates extending 5 perpendicularly to the direction in which the inductances move, the said inductances being positioned between the plates.

5. The combination defined in the preceding claim wherein the circuits are tuned to a desired 10 frequency when their inductances are spaced to provide loose coupling, so that when the inductances are moved closer together to provide close coupling, the circuits are slightly de-tuned due to the varying values of self-inductance of 15 the tuned circuit inductances with different spacings of the inductances from their respective conducting plates.

6. A high frequency coupling system comprising a pair of resonant circuits each including 20 reactance elements of opposite types and tuned to a selected frequency, a reactance common to and coupling said circuits, means for substituting for the coupling reactance between said circuits a common coupling reactance of different value 25 to vary the resonance band width of said system and for simultaneously inserting a supplemental reactance element in each of said circuits to prevent shifting of the resonance band in the frequency scale with variation in the band width. 30

7. A high frequency coupling system comprising a pair of resonant circuits each including inductance and a capacity, a second capacity common to and coupling said circuits, means for substituting for the coupling capacity between said 35 circuits a common coupling capacity of different value to vary the resonance band width of said system and for simultaneously inserting a supplemental capacity in each of said circuits to prevent shifting of the resonance band in the 40 frequency scale with variation in the band width.

8. A high frequency coupling system comprising a pair of resonant circuits each including inductance and a capacity, a second capacity common to and coupling said circuits, means for 45 substituting for the coupling capacity between said circuits a common coupling inductance to vary the resonance band width of said system and for simultaneously inserting a supplemental capacity in each of said circuits to prevent shift- 50 ing of the resonance band in the frequency scale with variation in the band width.

9. A high frequency coupling system comprising a pair of resonant circuits each containing inductance and capacitance and tuned to a selected frequency, said inductances having substantially zero mutual inductive coupling between them, a reactance common to and serving as the sole coupling means between said circuits, 55 means for adjusting the resonance band width of said system comprising means for substituting for the common coupling reactance a second common coupling reactance of different value, and means for simultaneously inserting a supplemental reactance in each of said circuits, 60 whereby shifting of the resonance band in the frequency scale co-incident with change of coupling is prevented. 65

10. A high frequency coupling system according to claim 9 wherein the common coupling reactance and the substituted coupling reactance are condensers. 70

11. A high frequency coupling system according to claim 9 wherein the common coupling re- 75

actance is a condenser and the substituted coupling reactance is an inductance coil.

12. In combination, a first pair of coupled tuned circuits, selectively operable common coupling reactances between said circuits, a second pair of coupled tuned circuits and selectively operable common coupling reactances therebetween, an auxiliary reactance included in each of the tuned circuits, means for simultaneously short-circuiting the auxiliary reactances and one of the common coupling reactances of the first pair of tuned circuits, means for simultaneously short-circuiting the auxiliary reactances and one of the common coupling reactances of the second pair of tuned circuits, and means interconnecting said short-circuiting means for operation in unison.

13. The combination according to claim 12, wherein the short-circuiting means are interconnected for unicontrol operation in a manner so that in one position, the auxiliary reactances of the first pair of tuned circuits will be short-circuited while those of the second pair will be operative, and vice versa in another position of the interconnected short-circuiting means.

14. In combination, a first pair of coupled

tuned circuits, selectively operable common coupling reactances between said circuits, one providing less than critical shape coupling and the other more than critical shape coupling, a second pair of coupled tuned circuits and selectively operable common coupling reactances therebetween, one providing less than critical shape coupling and the other more than critical shape coupling, an auxiliary reactance included in each of the tuned circuits, means for short-circuiting the auxiliary reactances of the first pair of circuits when its operative common coupling reactance is such as to provide more than critical shape coupling, means for short-circuiting the auxiliary reactances of the second pair of circuits when its operative common coupling reactance is such as to provide less than critical shape coupling, and means interconnecting said short-circuiting means for operation in unison.

15. The combination defined in claim 14 where-
in the selectively operable coupling reactances of the first pair of tuned circuits comprise a pair of condensers of different values, and those of the second pair of tuned circuits comprise a condenser and an inductance.

KENNETH W. JARVIS.
